WITNESS:

James L. Buck
INVENTOR
BY *Victor J. Evans*
ATTORNEY

UNITED STATES PATENT OFFICE.

JAMES L. BUCK, OF SHERMAN, TEXAS.

CARPENTER'S TOOL.

Application filed April 12, 1922. Serial No. 552,008.

To all whom it may concern:

Be it known that I, JAMES L. BUCK, a citizen of the United States, residing at Sherman, in the county of Grayson and State of Texas, have invented new and useful Improvements 5 in Carpenters' Tools, of which the following is a specification.

This invention relates to marking devices, particularly to squares for use by carpenters 10 and others, and has for its object the provision of a novel combined tri-square and marking square designed particularly for use upon siding such as is used on wooden buildings, the device being characterized by 15 the provision of a blade of peculiar formation which will conformingly engage against the surface of the siding so as to enable the carpenter or other operator to draw a line properly, the device being furthermore 20 adapted for use in the usual manner for trueing up and marking corner posts.

An additional object is the provision of a tool of this character which will be very simple and inexpensive in manufacture, easy 25 and rapid in use, efficient and durable in service and a general improvement in the art.

With the above and other objects and advantages in view, the invention consists in 30 the details of construction to be hereinafter more fully described and claimed, and illustrated in the accompanying drawings in which,

Figure 1 is an elevation of my device applied to a siding,

Figure 2 is a cross section on the line 2—2 of Figure 1 showing my device in end elevation,

Figure 3 is an elevation of the other 40 end of my device and

Figure 4 is a top edge view.

Referring more particularly to the drawings, the letter A designates a piece of siding such as is used in the construction of wooden 45 buildings and B designates one of the corner posts to which the siding is secured in the ordinary manner. It is of course well known that in actual practice a plurality of the pieces of siding are used, but I have shown 50 only one as it is believed that that is all which will be necessary to explain the operation of my device.

In carrying out my invention I provide a tool which consists of a handle 10 which may 55 be constructed of wood or metal and which may be of any desired dimensions. Mortised

into one end of this handle is a blade 11 which has its outer edge flush with the end of the handle and secured to the outer edge of the blade 11 and to the end of the handle 60 is secured a blade 12 which has its opposite edges so formed as to conformingly engage upon the siding A. The exact configuration of these edges depends of course upon the cross sectional shape of the particular siding 65 to be marked though in the drawings I have shown the device as formed for engagement upon a popular type of siding. The end of the blade 12 most remote from the handle 10 is formed with lateral extensions 13 which 70 are preferably apertured as shown at 14 to provide means whereby the device may be suspended from a nail or the like when not in use. The end of the blade 12 at the end of the handle is formed with lateral extensions 75 15 designed to project over the edge of the siding and formed with square shoulders 16 which engage the upper edge of the siding.

Secured to the other end of the handle 10 80 is a transverse member 17. This member 17 has both ends projecting beyond the sides of the handle 10 and these projecting ends are notched or recessed as shown at 18 for engagement upon the upper edge of the siding 85 and align with the shoulders 16 on the projections 15 of the blade 12.

In the use of the device it will be seen that when it is desired to cut square across a piece of siding the device is placed with the handle 90 10 extending longitudinally and with the blade 12 disposed transversely of the siding. One recess 18 and one shoulder 16 are engaged upon the edge of the siding while one edge of the blade 12 will conformingly engage 95 against the face of the siding. A line may then be drawn across the siding at the place where it is intended to make a cut. It is likewise to be noted that the device may be used as a tri-square in the ordinary manner and that it may also be used as a scribe or a guide for marking corner posts and the like as well as performing other kindred functions in wooden building construction.

From the foregoing description and a 105 study of the drawings it will be apparent that I have thus provided an extremely simple and inexpensive tool which will be very effective for the purpose specified and which will produce accurate work in a very easy 110 manner. Owing to the simplicity of the construction it is apparent that there is noth-

ing to get out of order and the device should have a long life and satisfactorily perform all the functions for which it is intended.

5. While I have shown and described the preferred embodiment of the invention, it is of course to be understood that I reserve the right to make such changes in the form, construction and arrangement of parts as will 10 not depart from the spirit of the invention or the scope of the subjoined claim.

Having thus described the invention I claim:

A device of the character described com-

prising a handle, a blade secured to one end 15 of said handle and having its end at the handle formed relatively wide and provided with aligned shoulders, the opposite edges of said blade being of curved shape to conform to the cross sectional configuration of 20 siding, and a member carried by the other end of the handle and formed with lateral extensions provided with shoulders in the same plane respectively with said first named shoulders.

25 In testimony whereof I affix my signature.

JAMES L. BUCK.
